UNITED STATES PATENT OFFICE.

FREDERICK DRISSELER, OF NEW YORK, N. Y.

SAFETY-LOCK FOR BROOCHES, SCARF-PINS, AND THE LIKE.

No. 823,517.

Specification of Letters Patent.

Patented June 19, 1906.

Application filed August 26, 1905. Serial No. 275,869.

To all whom it may concern:

Be it known that I, FREDERICK DRISSELER, a citizen of the United States, residing at New York, in the county of New York and State of New York, have invented certain new and useful Improvements in Safety-Locks for Brooches, Scarf-Pins, and the Like, of which the following is a specification, such as will enable those skilled in the art to which it applies to make and use the same.

This invention relates to brooches; scarf-pins, and other devices of this class; and the object thereof is to provide a pin of this class with a safety lock or attachment whereby when the lock or attachment is in use the pin cannot be accidentally or otherwise detached; and with this and other objects in view the invention consists in a device of the class specified constructed as hereinafter described and claimed.

The invention is fully disclosed in the following specification, of which the accompanying drawings form a part, in which the separate parts of my improvement are designated by suitable reference characters in each of the views and in which—

Figure 1 is a side view of an ordinary brooch-pin provided with my improvement; Fig. 2, an end view looking in the direction of the arrow x of Fig. 1; Fig. 3, a section on the line 3-3 of Fig. 1; Fig. 4, an enlarged view similar to Fig. 2, but showing the lock in a different position; Fig. 5, a side view of the device as shown in Fig. 4; and Fig. 6 a view similar to Fig. 3, but showing the lock in a different position, and in the accompanying drawings Figs. 4 to 6, inclusive, are on a scale larger than Figs. 1 to 3, inclusive.

In the drawings forming part of this specification I have shown at a the main part of an ordinary brooch, and said main part is provided at one end and at the back thereof with a stud a^2 , to which is pivoted a pin b , and the main part a of the brooch is provided at the opposite end or at the back thereof with a stud a^3 , having a hook member a^4 , which the pointed end of the pin b is adapted to engage through an opening a^5 in the usual manner and as shown in Figs. 1, 2, and 3, and the stud a^3 forms the base of the hook a^4 .

Pivoted in the stud a^3 is a hook-arm c , having a shank c^2 , which passes through said stud, as clearly indicated in Figs. 1, 3, and 5, and the shank c^2 is provided at the end opposite the hook-arm c with a lock-finger c^3 . The hook member a^4 is provided with a lug or pro-

jection a^6 , which extends parallel with the pointed end of the pin b and which the hook-arm c is adapted to engage when the lock is in operation, as clearly indicated in Figs. 2 and 3. The radius of the arc of movement of the free end of the hook-arm c is less than the distance between the lug or projection a^6 and the point where the shank c^2 of said arm passes through the stud a^3 , and the free end c^4 of the hook-arm c , which constitutes a part of the locking device, is curved upwardly and is adapted to pass over the lug or projection a^6 when said hook-arm is in its operative position, and the hook a^4 is also made slightly elastic or resilient, so that the free end thereof will be forced downwardly when the free end c^4 of the hook-arm c is forced over the lug or projection a^6 . When the hook-arm c is forced over the lug or projection a^6 or into the position shown in Figs. 1 to 3, inclusive, the finger c^3 , which constitutes a part of the lock, will be thrown into the position shown in Figs. 2 and 3, and the end thereof will be thrown approximately into engagement with the free end of the hook a^4 , as shown at d in Figs. 2 and 3.

In practice the pin b is passed through the material with which it is desired to connect the pin or brooch and is engaged with the hook a^4 , as shown in Figs. 1 to 3, inclusive. In this operation the hook-arm c is in the position shown in Figs. 4 and 6. After the pin b has been engaged with the hook a^4 , as shown in Figs. 2 and 3, the hook-arm c is forced forwardly into the position shown in Figs. 2 and 3, and this substantially closes the opening at a^5 made by the hook a^4 and through which the pointed end of the pin is passed into said hook, and when the parts are in this position the pin b cannot be detached from the hook a^4 and the brooch will remain securely attached to the garment or article to which it is applied or to which it is secured. In order to release the pin b from the hook a^4 , the hook-arm c must be forced backwardly into the position shown in Figs. 4 and 6, and this opens the hook a^4 , and at this time the pointed end of the pin b may be removed from the hook a^4 in the usual manner. It will be observed that the hook-arm c is of the same general form as the hook member a^4 , and when the parts are in operative position, as shown in Fig. 3, both the hook-arm and hook member engage the pin b and both form corresponding loops open on the same side, in which position the locking-finger c^3 , which is connected with the

locking-arm *c*, completes the loop formed by the hook member *a*⁴.

Having fully described my invention, what I claim as new, and desire to secure by Letters Patent, is—

In a device of the class described, a loop-shaped hook member open at one side and adapted to receive the pointed end of a pin, a locking-arm pivoted in the base of the hook member by means of a shank connected therewith and passing through said base, said shank being provided on the side of the base of the hook member opposite the locking-arm with a locking-finger adapted to be thrown into approximate engagement with

the end of the hook member so as to complete the loop formed thereby, and means whereby the locking-arm may be engaged with the hook member when said arm and finger are in their operative positions, substantially as shown and described. 20

In testimony that I claim the foregoing as my invention I have signed my name, in presence of the subscribing witnesses, this 25th day of August, 1905.

FREDERICK DRISSLER.
